SYSTEM OF CONVERTING DIRECT CURRENT

Raymond H. Sullivan, Rochester, N. Y., assignor
to General Motors Corporation, Detroit, Mich.,
a corporation of Delaware

Application June 10, 1938, Serial No. 212,963

1 Claim. (Cl. 175—365)

This invention relates to a system of converting direct current from low voltage to higher voltage, the output current being either direct or alternating, such system employing a vibratory interrupter operated by an electromagnet from the source of direct current. When a vibratory interrupter is used to control the circuits of the system, the electromagnet which operates the interrupter is controlled by contacts, one of which is actuated by the interrupter. The life of an interrupter is largely dependent upon the life of the contacts which control the vibrator magnet.

It is an object of the present invention to prolong the life and improve the operation of a vibratory interrupter for a D. C. transformer system by minimizing sparking at the contacts which control the electromagnet which operates the interrupter. In the disclosed embodiment of the present invention, the suppression of sparks at the magnet controlling contacts is obtained by a resistance in shunt with the electromagnet coil.

Further objects and advantages of the present invention will be apparent from the following description, reference being had to the accompanying drawing wherein a preferred embodiment of the present invention is clearly shown.

In the drawing:

A figure of the drawing is a wiring diagram showing a D. C. converter system embodying the present invention.

The source of direct current is the storage battery 20. The transformer, indicated at 21, comprises a core 22, primary windings 23 and 24 and secondary windings 25 and 26. The primary windings 23 and 24 are centrally tapped and connected by a wire 27 with the battery. The outside leads of the primary windings are connected by wires 29 and 30 respectively with stationary contacts 31 and 32 respectively of the vibratory circuit interrupter.

The vibratory circuit interrupter or vibrator comprises a flexible reed 33 fixed in a block 34 which is connected by a switch 35 to the battery 20. Reed 33 carries movable contacts 31a and

32a engageable, respectively, with contacts 31 and 32. At its lower end, the reed carries an armature 36 which is normally out of line with the pole face of a magnet core 37 surrounded by a magnet coil 38. The coil 38 is connected by wire 39 and wire 61 with wire 27 and by wire 40 with a stationary contact 41 which is normally engaged by a contact 42 fixed to the reed 33 by a leaf spring 43. The contacts 41 and 42 constitute the magnet controlling contact C. The letter R is applied to the magnet coil 38 to denote its resistance.

The vibrator is set into operation by closing the switch 35 which causes current to flow from the battery 20 through the magnet coil 38, thereby attracting the armature 36 of the vibrator into alignment with the upper face of the magnet core 37. This causes the reed 33 to move toward the right to bring the reed contact 32a into engagement with the stationary contact 32 and to separate the contact 42 from the contact 41. The engagement of contacts 32a and 32 causes a current to flow from the battery 20 through the transformer primary 24. The separation of the contact 42 from the contact 41 causes the magnet coil 38 to be disconnected from the battery, and its magnetism to diminish. However, the reed 33 continues to swing toward the right until its contact 32a is engaged with the contact 31. By this time, the magnetism of the coil 38 has diminished to zero thus permitting the reed by its own resiliency to swing back through its normal position and to the left of normal due to the momentum of reed and armature, thereby causing contact 32a to be separated from contact 32 and contact 31a to engage contact 31 which causes the transformer primary 23 to be connected with the battery. During the same movement of the reed to the left, the magnet controlling contacts 41 and 42 will reengage to effect the reenergization of the magnet 38, whereupon the cycle of operations of the reed is repeated. Therefore, the reed will continue to vibrate so long as the switch 35 remains closed and the two halves of the primary will be alter- 45

nately connected with the source of direct current, the battery 20.

The energization of the primary windings 23 and 24, alternately, effects the generation of voltages in the transformer secondaries, these voltages occurring alternately in opposite directions. If unidirectional current is desired, the secondary voltages may be rectified either by a mechanical vibrator rectifier associated with the primary interrupter or by means of a thermionic rectifier. The diagram shows a thermionic rectifying tube 50 having plates 51, connected with the ends of the transformer secondaries 25 and 26, and a cathode 52 connected by a filter choke 53 with an output terminal 54. The center tap of the transformer secondary is connected by line wire 55 with terminal 56. Filter condensers 57 and 58 connect the ends of choke 53 with output lead 55. The tube filament 59 is connected by wires 60 and 61 with switch 35 and battery 20.

I have thus far described a conventional form of D. C. converter system employing a vibrator, the magnet coil of which is controlled by contacts in series therewith. Without some means of suppressing sparking at the vibrator contacts C, the life of the contacts and hence of the vibrator will be relatively short. Therefore, some effective means for eliminating sparking at these contacts must be supplied. I employ, as a spark suppressor, a resistance 70 in shunt with the magnet coil 38, and I show by the following discussion how the requirements of spark elimination are met by a resistor of the proper value in shunt with the magnet coil winding. The letter r is also applied to the resistor 70 to indicate its resistance.

In the discussion which follows I assume, first, that the vibrator system is the conventional one without the shunting resistance 70.

When the contacts C close the battery voltage E is impressed on magnet coil 38. Voltage E is consumed by the counter generated voltage due to induction and the iR drop.

Let
 e =the counter generated volts due to induction.

i =the current in the coil at any instant after closing the contacts.

R =the resistance of the coil in ohms.

L =the inductance of the coil in henries.

Then

$$E = iR + e \quad (1)$$

$$e = L \frac{di}{dt} \quad (2)$$

and

$$E = iR + L \frac{di}{dt} \quad (3)$$

Equation 3 shows that at any time after closing of the contacts the counter generated volts and iR drop in the coil depends on the value of the instantaneous current i .

When

$$t = 0, iR = 0, \text{ and } e = E$$

and when

$$t = \infty, L \frac{di}{dt} = 0, \text{ and } iR = E$$

and

$$i = I$$

when I =the maximum steady current after the end of the transient.

The instantaneous current i at any time after closing the contacts may be determined as follows:

$$E = iR + L \frac{di}{dt} \quad 5$$

$$-L \frac{di}{dt} = iR - E \quad 10$$

$$- \frac{L}{R} \frac{di}{dt} = i - \frac{E}{R} \quad 10$$

$$\frac{di}{i - \frac{E}{R}} = - \frac{R}{L} dt \quad 10$$

$$\log \left(i - \frac{E}{R} \right) = - \frac{Rt}{L} + \log e \quad (4) \quad 15$$

$$i - \frac{E}{R} = \frac{Rt}{L} \quad 20$$

$$\frac{C}{C} = e \quad 20$$

$$i - \frac{E}{R} = C e^{-\frac{Rt}{L}} + \frac{E}{R} \quad 25$$

$$\text{When } t = 0, i = 0 \quad 25$$

$$0 = C + \frac{E}{R} \quad 25$$

$$C = - \frac{E}{R} \quad 25$$

$$i = \frac{E}{R} - \frac{E}{R} e^{-\frac{Rt}{L}} \quad 30$$

$$i = \frac{E}{R} \left(1 - e^{-\frac{Rt}{L}} \right) \quad 30$$

In order to reduce the sparking across contacts C to a negligible amount, the inductive voltage across contacts C must be kept at a value that will not cause sparking when the circuit is interrupted.

The magnitude of the voltage across the vibrator coil after the contacts open may be determined as follows:

On inspection of Equation 4 will show that after the contacts are closed for t seconds with circuit constants E, L and R, the current at the time of contact opening is i amperes.

Let it be assumed now that the battery voltage E is removed or made zero by the opening of the contacts. Then Equation 3 is:

$$0 = iR + L \frac{di}{dt} \quad (5) \quad 50$$

and

$$iR = -L \frac{di}{dt} = e_0 \quad (6) \quad 55$$

where e_0 =the inductive voltage across the coil and contacts when the contacts open.

Differentiating 6 gives:

$$e_0 = -L \frac{d}{dt} \left[\frac{E}{R} \left(1 - e^{-\frac{Rt}{L}} \right) \right] \quad 60$$

$$e_0 = E e^{-\frac{Rt}{L}} \quad (7) \quad 65$$

Equation 7 shows that regardless of the value of

$$\left(\frac{R}{L} \right)$$

when $t = 0, e_0 = E$, where R is the resistance of the circuit when the contacts are open. If, however, there were no resistance across the contact or across the coil at the time the contacts separate the resistance of the circuit would be infinity. Further examination of Equation 7 will show that 75

an infinite value of R will cause an infinitely high voltage to be generated across the coil and contacts. This would cause destructive sparking and short contact life.

5 If a resistor of resistance r were connected across the coil terminals the total resistance of the circuit at the time of discharge of coil energy would be $R+r$ ohms.

Substituting this in 7 gives:

$$10 \quad e_0 = E \epsilon \frac{(R+r)t}{L} \quad (8)$$

Equation 8 shows that the lower the value of r is made the lower the voltage across the contacts will be at the time of opening.

15 Since R and r are in parallel across the battery, r must not be made too low or an excessive current would be drawn and burn up the contacts. Therefore, the best value of r is the maximum value that may be used for the necessary reduction of sparking at the contacts. This will allow the use of minimum size resistor and maximum electrical economy.

20 The maximum value that r may be depends upon the speed of contact separation and contact material. This may be best determined experimentally for the contact breaker to be used.

25 Investigation on a typical breaker and vibrator coil showed that r may be as high as twenty times R , although a value of about ten times R would be better.

While the embodiment of the present invention as herein disclosed, constitutes a preferred form, it is to be understood that other forms might be adopted, all coming within the scope of the claim which follow.

What is claimed is as follows:

10 A system for converting low voltage direct current into higher voltage comprising a transformer having a divided primary, a source of direct current, a vibratory interrupter having a reed connected in series with the current source and center tap of the transformer primary, contacts 15 respectively connected with the ends of the transformer primary and engageable alternately with contacts carried by the reed, an armature carried by the reed, an electromagnet cooperating with 20 said armature and having a winding connected with the current source through normally closed contacts actuated by the reed, and means for reducing sparking at said contacts and comprising a non-inductive resistance in shunt with the magnet winding. 25
